DESIGN FOR A COMBINED CIGARETTE TRAY AND HOLDER

Gertrude Dubey, New York, N. Y.

Application November 28, 1945, Serial No. 124,151

Term of patent 3½ years

(Cl. D85—2)

To all whom it may concern:

Be it known that I, Gertrude Dubey, a citizen of the United States of America, residing in New York city, county of New York, and State of New York, have invented a new, original, and ornamental Design for a Combined Cigarette Tray and Holder, of which the following is a specification, reference being had to the accompanying drawing, forming part thereof.

Fig. 1 is a front perspective view of a combined cigarette tray and holder, showing my new design.

Fig. 2 is a rear perspective view thereof.

I claim:

The ornamental design for a combined cigarette tray and holder, substantially as shown.

GERTRUDE DUBEY.
